US00D822030S

(12) **United States Design Patent** (10) Patent No.: **US D822,030 S**
(45) Date of Patent: ** Jul. 3, 2018

(54) **DISPLAY BEZEL**

(71) Applicant: **Rockwell Collins, Inc.**, Cedar Rapids, IA (US)
(72) Inventors: **Sarah Barber**, Cedar Rapids, IA (US); **Felix B. Turcios**, Cedar Rapids, IA (US); **Ian G. Kiefer**, Mount Vernon, IA (US); **Bernard S. McCaffrey**, Cedar Rapids, IA (US)

(73) Assignee: **Rockwell Collins, Inc.**, Cedar Rapids, IA (US)

(**) Term: **15 Years**

(21) Appl. No.: **29/569,692**

(22) Filed: **Jun. 29, 2016**

(51) LOC (11) Cl. **14-02**
(52) U.S. Cl. **D14/450**

(58) **Field of Classification Search**

(57) **CLAIM**

The ornamental design for a display bezel, as shown and described.

DESCRIPTION

FIG. 1 is a perspective view of a display bezel showing our new design;

FIG. 2 is a front elevation view thereof;

FIG. 3 is a bottom plan view thereof;

FIG. 4 is a left side elevation view thereof;

FIG. 5 is a top plan view thereof;

FIG. 6 is a right side elevation view thereof; and,

FIG. 7 is a back elevation view thereof.

The broken lines in FIGS. 1-7 illustrate the environment of the claimed design and form no part thereof.

1 Claim, 7 Drawing Sheets
